Patented Aug. 12, 1919.

Inventor
George J. Ayres,
By his Attorney

W. C. Banfield

UNITED STATES PATENT OFFICE.

GEORGE J. AYRES, OF NEW YORK, N. Y.

HINGE FOR DOORS.

1,312,667.

Specification of Letters Patent.

Patented Aug. 12, 1919.

Application filed March 29, 1918. Serial No. 225,466.

To all whom it may concern:

Be it known that I, GEORGE J. AYRES, a citizen of the United States, and residing at New York, in the county of New York 5 and State of New York, have invented certain new and useful Improvements in Hinges for Doors, of which the following is a specification, such as will enable those skilled in the art to which it appertains to make and 10 use the same.

This invention relates to doors, gates, and like swinging closure devices, and the object thereof is to provide a device of this class which when swung in either direction 15 within certain limits and released will automatically return to the closed position, and which when swung in either direction at right angles to the closed position will automatically remain in the first named position 20 until force is applied to move it out of such position when it will automatically return to the closed position; a further object being to provide a structure of this class which does not involve springs or similar devices 25 but which operates entirely by gravity, and with these and other objects in view the invention consists in the construction, combination and arrangement of parts herein-after described and claimed.

30 The invention is fully disclosed in the following specification, of which the accompanying drawing forms a part, in which the separate parts of my improvement are designated by suitable reference characters in 35 each of the views, and in which:—

Figure 1 is a sectional view showing my improved door construction and the method of mounting and using the same;

Fig. 2 a longitudinal section on the line 40 2—2 of Fig. 1;

Fig. 3 a vertical section on the line 3—3 of Fig. 2; and

Fig. 4 a side view of a detail of the construction.

45 In the drawing forming part of this specification, I have indicated at *a* the top of a frame of a door, at *a*² the bottom of said frame and at *a*³ the back side face portion of said door frame, and at *b* I have indicated 50 a door mounted in said frame.

In the practice of my invention I countersink in the top door frame member *a* a plate *c* having a socket bearing *c*² and in the top 55 of the door is countersunk a corresponding plate *d* having a pivot pin *d*² adapted to

enter the socket bearing *c*². In the bottom frame member *a*² is countersunk a plate *e*, having a straight outer face *e*² and an arc-shaped inner face *e*³, and said plate is provided with a raised pivot pin *e*⁴ and at opposite sides thereof with cup-shaped recesses *e*⁵ with which communicates an arc-shaped groove *e*⁷, in the central part of which is a cup-shaped recess *e*⁸.

The top surface of the plate *e* is beveled 65 downwardly and inwardly in the direction of the recess *e*⁸, as clearly shown, and the side portions of the groove *e*⁷ between the recesses *e*⁵ and the recess *e*⁸ are also inclined downwardly and inwardly. In the bottom 70 of the door *b* and over the plate *e* is countersunk a plate or casting *f* which may be of any desired form in cross section but which is of irregular or angular shape in the construction shown, and which is provided with 75 a countersunk socket bearing *f*² adapted to receive the pivot pin *e*⁴ of the plate *e* and in the bottom of the part *f* inwardly of the socket bearing *f*² is countersunk a ball bearing *g* of well known form and construction, 80 and which comprises a casing *g*² the bottom of which is open and in which is placed a ball *g*³, which projects below the bottom of said casing and in the top of which is a ball race provided with bearing balls *g*⁴ 85 which rest on the ball *g*³, and in the operation of the device the ball *g*³ is adapted to move through the groove *e*⁷, or the separate side portions thereof and to enter the cup-shaped recesses *e*⁵ and *e*⁸. 90

In Figs. 1 and 2 of the accompanying drawing, the door *b* is shown in its closed position with the ball *g* resting in the recess *e*⁸ and if, when in this position, the door be swung in either direction and within an arc 95 of ninety degrees it will when released automatically return to the closed position, but if the door be swung through a complete arc of ninety degrees or at right angles to the closed position as indicated in dotted 100 lines in Fig. 2, the ball *g*³ will enter one of the recesses *e*⁵ and the door will automatically remain in the wide open position until force is applied to move it in the direction of the closed position into which it will automatically swing. 105

From the foregoing description it will be seen that the door when swinging from one position into another, as described herein, also moves vertically and for this reason the 110

vertical dimensions of the door are less than the vertical dimensions of the frame or other support or supports in which it is mounted.

The ball bearing device of which the ball 5 g^3 forms a part is of well known construction and in itself forms no part of my invention, and any suitable device of this class may be employed and from the foregoing description it will be seen that my improvement 10 does not involve hinges, springs or other devices of this class and is automatic in operation at all times, except for the effort made to open the door, or to move it out of its wide open position and, as hereinbefore stated, this construction may be 15 applied to doors, gates, shutters or any other closure devices, and the said construction may be made as strong and durable as necessary and will not easily get out of order in 20 use and thus render repairs necessary.

My invention is also not limited to the exact details of construction herein shown and described, and changes therein and modifications thereof may be made, within the scope 25 of the appended claims, without departing from the spirit of my invention or sacrificing its advantages.

It will also be seen from the foregoing description, that while I have shown and described 30 my improvement as applied to a door adapted to swing through half of a circle, my invention is not limited to this use thereof, as the same may be applied to a door, gate, shutter or other article adapted 35 to swing through an arc only of ninety degrees, in which event the groove e^7 need not be over forty-five degrees in length and only one socket recess e^5 will be necessary and other recesses e^5 in the groove e^7 may be 40 used regardless of the length of said groove, and whereby said door or other article might be held in an open position at an angle of forty-five degrees or less or more instead of at an angle of ninety degrees.

By reference to Figs. 1 and 4 of the drawings and as heretofore pointed out, it will be noted that the upper surface of the member e is inclined downwardly from that side adjacent which the depressions e^5 are located and in the general direction of the depression e^8 . Due to this inclination of the upper surface of the said member e , it is evident that the wall of the groove e^7 nearest the pintle e^4 will be higher than the opposite

wall of the said groove so that while the engagement of the bearing ball in this groove will exert a slight pull upon the member of the hinge in which it is mounted so as to cause the bushing f^2 to slightly bind the pintle e^4 to provide for smooth working of the parts of the hinge when the door is swung, there is on the other hand no tendency for the said bearing ball to ride out of the groove if the door is violently swung upon its hinges. 65

Having fully described my invention, what I claim as new and desire to secure by Letters Patent, is:—

1. A door hinge comprising members having coacting pintle elements, one of said members being formed with an arcuate groove concentric to its pintle element and inclined downwardly from each end toward its intermediate point, the member being further formed with a depression at each 70 end of the groove and with a depression at the intermediate point of the groove, the groove opening into the depressions and the depressions being of greater depth than the groove, and a bearing ball carried by the 75 other member to travel in the groove and to seat in the said depressions in different positions of swinging movement of the door.

2. A door hinge comprising members having coacting pintle elements, one of said members being formed with an arcuate groove concentric to its pintle element and inclined downwardly from each end toward its intermediate point, the member being further formed with a depression at each 80 end of the groove and with a depression at the intermediate point of the groove, the groove opening into the depressions and the depressions being of greater depth than the groove, and a bearing ball carried by the 85 other member to travel in the groove and to seat in the said depressions in different positions of swinging movement of the door, the wall of the groove nearer the pintle element being higher than the opposite wall. 90

In testimony that I claim the foregoing as my invention I have signed my name, in presence of the subscribing witnesses, this 27th day of March, 1918.

GEORGE J. AYRES.
